UNITED STATES PATENT OFFICE.

ALBERT E. TUTTLE, OF BOSTON, MASSACHUSETTS.

MIXING TROUGH.

Application filed April 3, 1926. Serial No. 99,483.

This invention relates to mixing troughs in which hair is adapted to be blown into lime putty in a fluid state during the process of manufacturing plaster or mortar.

5 The object of the invention is to provide means for preventing the hair entering the trough from winding around the mixing shaft or clogging the mixing blades while the two ingredients, lime putty and hair, are being mixed and conveyed endwise of the trough to be delivered to a mixing receptacle where a third ingredient such as sand is to be added to the mixture.

This object is attained by the mechanism 15 illustrated in the accompanying drawings.

For the purpose of illustrating the invention, one preferred form thereof is illustrated in the drawings, this form having been found to give satisfactory and reliable 20 results, although it is to be understood that the various instrumentalities of which the invention consists can be variously arranged and organized, and the invention is not limited to the precise arrangement and organization of these instrumentalities as herein shown and described except as required by the scope of the appended claims.

Of the drawings:

Figure 1 represents a plan of an apparatus 30 for making plaster and mortar and including a mixing trough embodying the principles of the present invention.

Figure 2 represents a vertical section of the mixing trough on line 2, 2, on Fig. 1.

Figure 3 represents a plan of the stirring and mixing element of said trough, and

Figure 4 represents an elevation of one of the helical blades prior to its being curved and mounted upon the rotary cylinder of 40 the mixing trough.

Similar characters indicate like parts throughout the several figures of the drawings.

In the drawings 10 is a delivery pipe from 45 which lime putty in a fluid state may be ejected down a chute 11 into one end of a mixing trough 12.

A hair shredding machine 13 ejects a supply of hair through a conduit into said 50 trough 12 at a point intermediate its ends.

The opposite or delivery end of the trough 12 communicates with a mixing receptacle 14 to which sand is delivered from a hopper 15 by means of an endless apron 16.

55 These various mechanisms form no part of

the present invention and therefore need no detailed description.

Heretofore, in mixing troughs where shredded hair is blown into the lime putty the hair becomes wound around the mixer 60 shaft, gathers in bunches, and otherwise clogs up the mixing devices.

This is very objectionable as must be quite obvious and the present invention is entirely for the means to overcome these difficulties. 65

To accomplish this desired result the usual mixer shaft 17 has mounted thereon collars 18 disposed within the opposite ends of a cylinder 19 having inclined blades 20 radiating therefrom. 70

The shaft 17 is mounted in bearings at the ends of the mixing trough 12 and is rotated by the same means that actuates the endless apron 16.

The circumference of the cylinder 19 is 75 twice as great as the length of any hair discharged into the trough. As a consequence of making the cylinder of large diameter and great circumference, no hair admitted to the lime putty can possibly be wound 80 around the cylinder.

By this means this difficulty is overcome and the hair will not become lodged between the various stirring blades thereby preventing the proper operation of the mixing elements. 85

Generally, blades and pins have been used to stir the mixture, these members having straight sides and the hair has been quite apt to wind around these elements and collect in bunches, instead of becoming separated throughout the mass of lime putty as is desired. 90

In the present mixing trough the inclined blades 20 project from the periphery of the cylinder 19, substantially in the form of an interrupted helix, said blades being of sheet metal and welded or otherwise secured to the metal cylinder 19. 95

As a consequence when the shaft 17 is 100 rotated in the direction of arrow *a* on Fig. 2 of the drawings, the blades 20 will cut through the contents of the trough and force the material toward the delivery end of the trough owing to the inclination of said 105 blades.

The edge of each blade 20 gradually increases in height from the forward end 21 to the rear end 22 thereof. As a consequence of this gradual increase in height of the 110

blades 20, no hair can collect around the edge thereof, for as the shaft 17 continues to rotate any hair in front of the edge of a blade 20 will be carried outwardly thereby away from the axis of said shaft.

This results in all the hair being separated and moved outwardly in a direction where in separated condition it will commingle with the lime putty, thereby producing a perfect mixture of these two ingredients as it is delivered into the mixing receptacle 14 to be further mixed with sand added to the mixture.

This is of great advantage as otherwise a very inferior product will be obtained in which masses of hair will be scattered in spots with other portions of the product entirely devoid of the necessary binding material.

Such inferior product can only be sold at great loss.

Moreover, by applicant's construction there can be no hair winding around the shaft or clogging the mixing blades thereby preventing the free rotation of the shaft.

It is believed that the operation and many advantages of the invention will be fully understood without further description.

Having thus described my invention, I claim—

1. In a mixing trough adapted to receive lime putty in a fluid state at one end thereof and deliver it from the opposite end, said trough being associated with means for blowing short lengths of shredded hair into said trough; a rotatable member extending lengthwise of said trough; and a plurality of blades radiating from said member and inclined to the axis thereof, and all having their forward edges gradually increasing in height.

2. In a mixing trough adapted to receive lime putty in a fluid state at one end thereof and deliver it from the opposite end, said trough being associated with means for blowing short lengths of shredded hair into said trough; a rotatable member extending lengthwise of said trough; and a plurality of blades radiating from said member and inclined to the axis thereof, and all having their forward edges tangential to the periphery of said member and gradually increasing in height.

3. In a mixing trough adapted to receive lime putty in a fluid state at one end thereof and deliver it from the opposite end, said trough being associated with means for blowing short lengths of shredded hair into said trough; a rotatable member extending lengthwise of said trough; and a plurality of thin blades radiating from said member

with their bases secured directly thereto at an inclination to the axis thereof, and all having their forward edges gradually increasing in height.

4. In a mixing trough adapted to receive lime putty in a fluid state at one end thereof and deliver it from the opposite end, said trough being associated with means for blowing short lengths of shredded hair into said trough; a rotatable member extending lengthwise of said trough and having a circumference more than twice the length of any hair blown into said trough; and a plurality of blades radiating from said member and inclined to the axis thereof and all having their forward edges gradually increasing in height.

5. In a mixing trough adapted to receive lime putty in a fluid state at one end thereof and deliver it from the opposite end, said trough being associated with means for blowing short lengths of shredded hair into said trough; a rotatable member extending lengthwise of said trough; and a plurality of blades radiating from said member and inclined to the axis thereof, said blades being disposed in two rows on opposite sides of said member and all having their forward edges gradually increasing in height.

6. In a mixing trough adapted to receive lime putty in a fluid state at one end thereof and deliver it from the opposite end, said trough being associated with means for blowing short lengths of shredded hair into said trough; a rotatable member extending lengthwise of said trough; and a plurality of blades radiating from said member and inclined to the axis thereof, and all having their forward edges gradually increasing in height, said blades being disposed in two rows on opposite sides of said member, and the blades of one row being intermediate the blades of the other row.

7. In a mixing trough adapted to receive lime putty in a fluid state at one end thereof and deliver it from the opposite end, said trough being associated with means for blowing short lengths of shredded hair into said trough; a rotatable member extending lengthwise of said trough consisting of a cylinder closed at both ends mounted upon and rotatable with a central shaft; and a plurality of blades radiating from said member and inclined to the axis thereof, said blades being disposed in two rows on opposite sides of said member and all having their forward edges gradually increasing in height.

Signed by me at 746 Old South Bldg., Boston, Mass., this 31st day of March, 1926.
ALBERT E. TUTTLE.
